UNITED STATES PATENT OFFICE.

JOSEPH WOLFF, OF BROOKLYN, NEW YORK, ASSIGNOR TO SONORA PHONOGRAPH CORPORATION, A CORPORATION OF NEW YORK.

DESIGN FOR A CASING FOR SOUND-BOXES.

52,155.

Specification for Design.

Patented July 2, 1918.

Application filed March 10, 1917. Serial No. 154,044. Term of patent 14 years.

To all whom it may concern:

Be it known that I, JOSEPH WOLFF, a subject of His Majesty the King of Great Britain, residing in the borough of Brooklyn, county of Kings, city and State of New York, have invented a new, original, and ornamental Design for a Casing for Sound-Boxes, of which the following is a specification, reference being had to the accompanying drawings, forming a part thereof.

In the drawings,—

Figure 1 is a rear view of a casing for

sound-boxes illustrating my improved design;

Fig. 2 is a side elevation of the same.

I claim:

The ornamental design for a casing for sound-boxes, substantially as shown.

This specification signed and witnessed this 2nd day of March, 1917.

JOSEPH WOLFF.
